UNITED STATES PATENT OFFICE

2,031,576

HEATING AND COOLING UNIT FOR
BUILDINGS

George W. Saathoff, South Orange, N. J., assignor to Doherty Research Company, New York, N. Y., a corporation of Delaware

Application October 26, 1934, Serial No. 750,065

2 Claims. (Cl. 257—8)

This invention relates to air conditioning systems, and more particularly to an improved method of and apparatus for ventilating and heating or cooling buildings.

5 An important object of the invention is to provide a ventilation system for buildings according to which each room or unit space in the building has an individual air conditioning unit.

Another object of the invention is to provide 10 an air conditioning system in which the temperature of the air is raised in winter and lowered in summer by indirect heat transfer with a circulating fluid such as water.

Hot water is an ideal medium to use for heating 15 indirectly the air employed in ventilating a building, because of its high heat capacity and conductivity. For the same reason cold water is an ideal medium to use for cooling by indirect heat transfer the air employed for ventilation of a 20 building.

A particular object of the invention is to provide method and apparatus for conditioning air in which circulating water may be used as a heat transfer medium for either heating or cooling the 25 air, and in which the system employed in heating is also employed, with relatively simple modification, for cooling.

With the above and other objects and features 30 in view, the invention consists in the improved method of and apparatus for ventilating, heating and cooling buildings which is hereinafter described and more particularly defined in the accompanying claims.

A preferred arrangement of the apparatus 35 forming a part of the invention is illustrated in the accompanying drawing, which shows somewhat diagrammatically, with parts in vertical section and parts in elevation, the arrangement of multiple air conditioning units and water heating and cooling system which make up the apparatus.

In the drawing a small portion of a building is shown, including an outside wall 10, a basement 12 having a floor 14, and the first and second 45 floors 16 and 18 above the basement, with windows 20 opening into the rooms of each floor. In each room or suite of rooms of the building there is at least one individual air conditioning unit 22 which may consist, as shown in the drawing, of 50 a form of radiator housing 24 mounted beneath a window 20. Each air conditioning unit 22 consists essentially of the housing 24 within which there is mounted a radiator 26 and an air circulating fan 28. An air inlet 30 is formed in the 55 front wall of the housing to permit circulation

of air from the room through the housing, and conditioned air passes out from the housing into the room through an outlet 32 located in the top of the housing. A fresh air inlet passage 34, provided with a filtering screen 36 and a damper 38, communicably connects the interior of the housing with the outside air. By controlling the setting of damper 38, suitably proportioned amounts of fresh air and recirculated air from the room are drawn by fan suction over the radiator 26, and the conditioned air is then forced under positive fan pressure into the room through outlet register 32.

The radiators 26 illustrated are the air temperature conditioning elements of a closed water 15 circulating system which includes a circulating pump 40, pipe coil 42 mounted in a pressure resistant heat exchange tank 44, together with an expansion tank 46 having an overflow vent 48 at the top of the circuit, and circulating feed and 20 return pipes 50 and 51 connecting pump 40, coil 42, and radiators 26 in closed circuit. A water supply pipe 52 is provided to introduce make-up water to the circuit above described.

For the purpose of supplying heat to the system above described, the heat exchange tank 44 is provided with a valved inlet pipe 54 through which a heating fluid, preferably steam, may be introduced into tank 44 in direct heat exchange relation with coils 42 of the water circulating system. Temperatures within tank 44 are regulated by the steam pressure maintained therein. Condensate is removed from a sump 56 located in the bottom of tank 44 through a discharge pipe 58 and thence out of the system through a valved exhaust line 60.

For the purpose of cooling the ventilating air for the building during warm weather, the same water circulating system and air conditioning units are employed, but the tank 44 is equipped 40 for operation as an evaporation cooling unit. For this purpose a suction pump 62 is provided having its inlet connected by a valved pipe 64 with the interior of tank 44. The discharge side of pump 62 is connected by pipe 64 with a condenser 66. A second suction pump 68 is also preferably mounted in the air discharge pipe 70 from the condenser. An air port valve 71 is mounted in pipe 70. A cooling fluid such as water is passed through coil 72 in condenser 66, and condensate 45 is discharged therefrom through a pipe 74. One or more spray pipes 76 are mounted in tank 44, preferably in position to spray water downwardly over the coils 42. Sprays 76 are connected by a valved pipe 78 in closed circuit with a radi-

ator 80 and discharge pipe 58 leading off from the sump 56 in tank 44, and a circulating pump 82 is embodied as an element in this circuit. The circuit including sprays 76, tank 44, pipes 58 and 5 78, radiator 80 and pump 82, is supplied with make-up water by a valved supply pipe 83.

In operating the unit as a cooling system, valve 84 in steam supply pipe 54 is closed, as is also valve 86 in exhaust line 60. Water is supplied 10 by pipe 83 to the circuit including sprays 76, and pumps 62 and 68 and condenser 66 are placed in operation and communicably connected with tank 44 by opening valve 90 in pipe 64. The water circulating through the air conditioning 15 system including radiators 26 is cooled during its passage through the coils 42 in tank 44 owing to the evaporation of some of the water which is projected into the tank and over the coils through sprays 76. The temperature which is maintained 20 in tank 44 is regulated by controlling the degree of vacuum impressed on the tank by pumps 62 and 68. Water vapor which is removed from the tank through the suction line 64 is condensed in condenser 66 and discharged from the system 25 through pipe 74. The water which is not evaporated in tank 44 has its temperature lowered by the evaporation taking place therein, and can therefore be used for cooling the basement 12 by circulating it through the radiators 80. Make- 30 up water is of course added to this circuit as needed from the water supply system of the building through pipe 83.

The illustrated embodiment of the invention 35 explains the principles of apparatus design and air conditioning operation which have formed the basis for a successful system now operating in a large office building. For tall office buildings several water circulating circuits are preferably used, each of which includes in its zone

all of the radiators 26 on a plurality of floors of the building. While water is the preferred heat transfer medium, other liquids, such as oil, may be used to advantage in particular installations.

The invention having been thus described, what 5 is claimed as new is:

1. Apparatus for heating and cooling buildings comprising, an air conditioning chamber, a radiator mounted in said chamber in the path of air flowing therethrough, a heat exchanger having 10 coils therein, water circulating tubes connecting the coils of said heat exchanger in closed circuit with said radiator and with a circulating pump, means for introducing a heating fluid into said heat exchanger around said coils, means for 15 spraying water into said heat exchanger around said coils, and a vacuum pump having its inlet connected to said heat exchanger whereby water may be evaporated within said heat exchanger.

2. A water heating and cooling system for buildings including a plurality of radiators, an evaporation chamber, a pipe coil heat exchanger mounted within said evaporation chamber, a water circulating pump, an expansion chamber, 25 circulating tubes connecting the radiator, pipe coil, pump and expansion chamber in a closed circuit, a valved steam supply pipe connected to discharge into said chamber, a vacuum pump having its inlet communicably connected to said chamber, a spray device mounted in the upper part of said chamber, a liquid removal pipe connected to the bottom of said chamber, a radiating element connected to said removal pipe, and means including a second circulating pump and tubing communicably connecting said removal pipe and radiating element in closed circuit with the spray device and chamber.

GEORGE W. SAATHOFF.
